UNITED STATES PATENT OFFICE.

WILLIAM L. WHITE, OF OLD ORCHARD, MAINE.

DESIGN FOR A COMBINED SEAT AND TABLE.

54,882.

Specification for Design.

Patented Apr. 13, 1920.

Application filed October 13, 1919. Serial No. 330,505. Term of patent 7 years.

To all whom it may concern:

Be it known that I, WILLIAM L. WHITE, a citizen of the United States, residing at Old Orchard, in the county of York and State of Maine, have invented a new, original, and ornamental Design for a Combined Seat and Table, of which the following is a specification, reference being had to the accompanying drawing, forming part thereof.

Referring to the drawings:

Figure 1 represents a plan view of a combined seat and table, showing my new design.

Fig. 2 is a front elevation of the same.

Fig. 3 is a detail transverse section taken on the line 3—3 of Fig. 1.

I claim:

The ornamental design for a combined seat and table, as shown.

In testimony whereof I have hereunto set my hand in presence of two subscribing witnesses.

WILLIAM L. WHITE.

Witnesses:

FRANKLIN E. LOW,
CHARLES S. GOODING.
